HANDLE ADAPTER FOR CIRCUIT BREAKERS

Ronald Nicol, Trenton, N.J., assignor to Heinemann
Electric Company, Trenton, N.J.

Original design application Apr. 19, 1973, Ser. No. 352,712, now Patent No. 233,760, which is a division of design application Ser. No. 159,104, July 1, 1971, now Patent No. 227,903, which in turn is a continuation-in-part of design application Ser. No. 21,039, Jan. 22, 1970, Divided and this application Oct. 2, 1974, Ser. No. 511,482

Term of patent 14 years

Int. Cl. D13—03

U.S. Cl. D26—13 R

Fig. 4.

Fig. 1.

Fig. 2.

Fig. 3.

FIG. 1 is a side elevation view of a handle adapter for a circuit breaker;

FIG. 2 is a front elevational view;

FIG. 3 is a bottom plan view; and

FIG. 4 is a top plan view.

The portions of the figures shown in broken lines are shown for illustrative purposes only.

This is a divisional application of application Ser. No. D. 352,712, filed Apr. 19, 1973, now Pat. No. D. 233,760, which is a division of Ser. No. 159,104, filed July 1, 1971, now Pat. No. 227,903, which is a continuation-in-part of Ser. No. 21,039, Jan. 22, 1970.

I claim:

The ornamental design of a handle adapter for circuit breakers, as shown.
